MULTICYLINDER COMBUSTION
ENGINE

Friedrich Sass, Charlottenburg, Germany, assignor to General Electric Company, a corporation of New York

Application March 18, 1935, Serial No. 11,697
In Germany March 13, 1934

5 Claims. (Cl. 60—16)

The present invention relates to multi-cylinder combustion engine arrangements including two cylinders or groups of cylinders, of which a first cylinder or group of cylinders receives fuel immediately during starting and reversing, whereas a second cylinder or group of cylinders receives at first starting air and fuel only after the first cylinder or group of cylinders has ignited. Difficulties have been experienced with arrangements of this kind because the starting air supplied to the second cylinder or group of cylinders causes cooling of the cylinders and excessive stresses are set up in the cylinders whenever the cylinders are fully charged with fuel immediately after the starting air supply is shut off, that is, immediately after the first cylinder or group of cylinders has ignited.

The object of my invention is to provide an improved construction and arrangement of the type of combustion engine arrangements above specified, whereby said excessive stresses are considerably reduced. This is accomplished in accordance with my invention by the provision of means for preventing sudden full charge of the second cylinder or group of cylinders immediately after the starting air has been shut off. The charging of the second group of cylinders is effected gradually and somewhat later, preferably by a manually controlled element. With such an arrangement, sudden changes in temperature of the second cylinder or group of cylinders during the starting operation and the consequent bursting of cylinder liners or heads are prevented or reduced.

Another advantage of my arrangement is that the combustion engine as a whole is less accelerated during the starting. Excessive stresses of the engine material, therefore, are avoided during the starting. This is of special significance in connection with ships' engines which are often started and reversed.

The invention is also specially advantageous in connection with double-acting cylinders in which air is supplied to the lower ends of the cylinders during starting.

For a better understanding of what I believe to be novel and my invention, attention is directed to the following description and the claims appended thereto in connection with the accompanying drawings which forms a part of my specification.

In the drawings, Fig. 1 is a diagrammatic view, partly in perspective, of an engine arrangement in accordance with my invention, Fig. 2 is a diagrammatic view of the arrangement of Fig. 1 in a certain position during the starting operation, Figure 3 is a sectional view along the line 3—3 of Figure 1 and Figure 4 is a fragmentary section through a fuel pump and air supply de-

vice associated with one of the group of cylinders 11 in Figure 1.

The arrangement comprises two cylinders or groups of cylinders, a first cylinder or group of cylinders 10 and a second cylinder or group of cylinders 11. Means including a conduit 12 are provided for conducting compressed air to the second group of cylinders 11 during starting operation. The conduit 12 of each engine cylinder is connected to an air chamber 12a arranged to receive compressed air through a conduit 12b. The flow of air from the conduit 12b to the conduit 12 is controlled by a valve 12c actuated by a lever 12d having a projection 12e in alignment with the end of the stem of the valve 12c. One end of the lever 12d projects into a recess 12f of the reciprocating pump 14 and the other end is eccentrically connected by means of a link 12g to an adjustable fulcrum 12h. During normal operation, the lever 12d and the fulcrum 12h are positioned so that up and downward movement of the left-hand end of the lever 12d does not affect operation of the valve 12c. During starting the adjustable fulcrum 12h is turned to move the right-hand end of the lever 12d upward so that movement of the lever 12d by the reciprocating pump 14 effects opening of the valve 12c, resulting in the periodic supply of compressed air to the corresponding cylinder. It will be understood that conduit 12 has the usual check valve therein to prevent back pressure in the air line upon expansion of combustion gases in the cylinder under normal running conditions. Such arrangement for controlling the supply of compressed air is known in the prior art and is more fully disclosed in the British Patent No. 272,087. During starting, fuel is supplied immediately to the first group of cylinders 10 and fuel is supplied to the cylinders 11 only after the air supply to said cylinders has been shut off, that is, after ignition in the first cylinders 10. The means for supplying fuel to the cylinders includes pumps. In the present instance I have indicated a group of three pumps 13 for supplying fuel to the cylinders 10 and a group of three pumps 14 for supplying fuel to the cylinders 11 through conduit 62. The pumps are actuated by a cam shaft 15 having cams 16 which engage rollers 17 secured to extensions of pistons 18 of the pumps. Each group of pumps has a casing 19 and each pump includes a fuel supply valve 20, a fuel discharge valve 21 and a relief valve 22. The effective pump stroke in this particular instance is regulated by means affecting the relief valve 22. This means includes with respect to each pump a control lever 23 connected to the pump piston and supported on an eccentric 24. The eccentrics 24 of the first group of pumps 13 are held on a first regulating shaft 25 and the eccentrics 24 of the second group of
